BREATH INPUT UNIT FOR A BREATH TESTER

Samuel Shiber, Chicago, and Joseph P. Hoppesch, Streamwood, Ill., assignors to Borg-Warner Corporation, Chicago, Ill.

Filed Oct. 8, 1971, Ser. No. 187,723

Term of patent 14 years

Int. Cl. D24—02

U.S. Cl. D83—1 N

FIG. 1

FIG. 2

FIG. 3

FIG. 1 is a perspective view of a breath input unit for a breath tester showing our new design;

FIG. 2 is an enlarged side elevational view of part of the breath input unit of FIG. 1; and

FIG. 3 is an end view of the breath input unit of FIGS. 1 and 2.

We claim:

The ornamental design for a breath input unit for a breath tester, as shown.
